ROTARY DRILL CUTTER

Guy E. Behnke, Oklahoma City, Okla., assignor to
 Chicago Pneumatic Tool Company, New York,
 N. Y., a corporation of New Jersey

Application July 11, 1940, Serial No. 344,855

2 Claims. (Cl. 255—71)

This invention relates generally to roller cutters for use in earth boring bit assemblies, and more particularly to the tooth formation of such cutters.

One object of the invention is to enable a bit assembly to function effectively under relatively light drilling pressure.

Another object of the invention is to obtain coarse cuttings of the material being cut in order that the various formations encountered in drilling a well may be easily identified and correctly logged.

According to the present invention these objects are attained through a distribution of the cutting teeth among the several cutters of a bit assembly which effects a reduction in cutting area and so spaces certain rows of teeth that these teeth act to chip or loosen some material from the formation instead of disintegrating it.

Another object of the invention is to obtain a distribution of cutting teeth that will offer the least resistance to penetration and still provide for uniform wear.

A feature of this aspect of the invention lies in an arrangement of teeth at the apex portion of the cutter which permits these teeth also to penetrate deeply into the earth formation.

Other objects and structural details of the invention will be more apparent from the following description when read in conjunction with the accompanying drawing, wherein:

Fig. 1 is a view partly in elevation and partly in longitudinal section of a bit assembly embodying the cutter construction of this invention; and

Fig. 2 is a view of the assembly shown in Fig. 1, looking upward from below the assembly.

The invention is disclosed as embodied in a bit assembly of the type having three cooperating roller cutters of generally conical shape. It should be understood, however, that this disclosure is merely illustrative since the invention may be embodied in bit assemblies having a greater or lesser number of cutters than three.

Referring to Fig. 1 of the drawing the assembly comprises a split type bit head 10 having an upwardly extending shank 11 adapted for threaded engagement with a rotary drill stem. The lower end of the bit head is formed with three separate depending portions 12 each of which carries a bearing (not shown) supporting a roller cutter 13. The cutters 13 are generally conical in shape, extend inwardly towards the longitudinal axis of the bit head 10 and are arranged with their longitudinal axes perpendicu-

lar to the inner wall of their respective supports 12. The cutters 13 project below the bit head 10 in position to engage the bottom of the drill hole. During operation of the drill the rotary movement of the bit head causes the cutters to revolve about the bit axis. By reason of their engagement with the bottom of the drill hole, the cutters are further constrained to roll over the earth formation.

In order that the formation may be loosened or cut away and the drill hole thereby formed, the surface of each cutter is formed with a plurality of circumferential rows of penetrating teeth. Adjacent the base of each cutter is a row 14 of relatively wide teeth which maintain the gauge of the drill hole and cut clearance for the bit head. The teeth 14 are formed on a peripheral zone 15 which tapers inward toward an imaginary apex which is in line with the axis of rotation of the cutter and far beyond the axis of revolution of the bit. The zone 15 merges with another zone 16 tapering at a less acute angle toward an apex substantially at the intersection of the cutter and bit axes. Zone 16 comprises an apex portion 18 at its tip, and an intermediate portion extending between said apex portion and the zone 15. Each cutter has one or more circumferential rows of pyramidal or pick-point teeth 17 arranged on the intermediate portion of the cutter. Preferably, one of the rows on one cutter is positioned at the intersection of the zone 16 with the base zone 15. Formed on the apex portion 18 of each cutter is a pair of blade-like teeth 19 and two sets of pyramidal shaped teeth 21. The teeth 19 are oppositely disposed on the apex portion 18 and have respective longitudinal cutting edges which taper inward to a point at the very tip of the apex, thereby simulating the shape of a spear point. The sets of teeth 21 are arranged at the base of the apex portion 18 with the respective sets occupying positions on opposite sides of the apex between the blade-like teeth 19. The apex teeth 21 and intermediate teeth 17 are all of approximately the same size and shape and penetrate the formation to substantially the same extent.

The apices of the several cutters lie adjacent one another and substantially adjacent the longitudinal axis of the bit head 10. The apex teeth 19 occupy the same relative positions on all three cutters, and follow the same general path around the center of the drill hole. The pyramidal teeth 21 roll over a part of the area cut by the teeth 19. To prevent the apex portion of one cutter from tracking in the ridges cut by another cut-

ter, it is desirable to provide two cutters with a different number of pyramidal teeth 21. As shown in the drawing, there are four such teeth on one cutter and two on each of the others. Through the cooperation of the several sets of apex teeth the central portion of the hole is cut rapidly and efficiently and the wear incident to the work is distributed evenly among the cutters.

The intermediate rows of teeth 17 are so distributed among the cutters as to cut away by their combined action the earth formation between the base teeth 14 and the apex teeth 19-21. The row or rows of teeth on each cutter are offset with respect to corresponding rows on the companion cutters and follow a separate path along the bottom of the drill hole. Unlike the conventional cutters of this type, however, the rows of teeth 17 do not combine to cut adjacent paths but are so spaced as to cut paths separated from each other by uncut ridges of formation. In brittle formations these uncut ridges chip and are readily broken up into coarse relatively large cuttings. The non-true rolling motion of the cutter results in a slight twisting movement by the teeth as they penetrate, thereby facilitating the chipping action. In shales and hard packed clays the side walls of the teeth 17 press against the uncut ridges and so loosen the formation as to permit it to be carried away by the usual hydraulic flushing means. This spacing of the rows of teeth 17 results in a reduction in cutting area and a corresponding increase in cutting speed. The increased cutting speed is obtained because the weight of the drill is concentrated upon a smaller supporting area, thus causing a deeper penetration of the teeth. Since some earth formations are more readily chipped than others the spacing of the rows of teeth 17 is determined by the kind of formation being cut. To obtain the greatest efficiency of operation a plurality of dif-

ferently constructed cutter assemblies may be provided for selective use.

It will be further noted that the reduction in cutting area permits effective use of the bit assembly under less weight than is necessary for operation of the conventional assembly. It is a well known fact that excessive weights tend to cause the cutters to follow inclined formation strata and depart from the desired course through the earth.

What is claimed is:

1. A bit assembly comprising a bit head, a plurality of generally cone shaped roller cutters supported on said bit head, each of said cutters having an apex portion lying adjacent the longitudinal axis of said bit head, a plurality of blade-like teeth formed on said apex portion, said teeth tapering from rearmost points of maximum height at the base of said apex portion inward toward the axis of the cutter and terminating adjacent the tip of said apex portion, a plurality of pyramidal teeth formed on the base of said apex portion defining in cooperation with the rearmost points of said blade-like teeth an inner circumferential row of pointed teeth, and an outer circumferential row of teeth on each of said cutters, the teeth of which conform in size and shape to the teeth of said inner row.

2. A bit assembly according to claim 1, characterized in that each of said inner circumferential rows of teeth is spaced a distance from the longitudinal axis of said bit head causing it to move in the same path followed by corresponding rows of teeth on the companion cutters, while each of the outer circumferential rows of teeth is spaced a distance from the longitudinal axis of said bit head causing it to move in a path spaced from the paths followed by corresponding rows of teeth on the companion cutters.
